UNITED STATES PATENT OFFICE.

WILLIAM SMITH, OF PHILADELPHIA, PENNSYLVANIA.

DESIGN FOR A MOLDING.

SPECIFICATION forming part of Design No. 14,893, dated March 18, 1884.

Application filed February 11, 1884. Term of patent 7 years.

To all whom it may concern:

Be it known that I, WILLIAM SMITH, a citizen of the United States, and a resident of Philadelphia, Pennsylvania, have invented or produced a new and original Design for a Strip of Molding, of which the following is a specification.

My design is shown in the accompanying drawings, Figures 1 and 2 showing two forms 10 of molding embodying the design, Fig. 3 being a plan view of Fig. 1, and Fig. 4 a vertical section on the line 1 2, Fig. 1, and Fig. 5 being a plan view of Fig. 2, and Fig. 6 a vertical section on the line 3 4, Fig. 2.

15 The design comprises a strip having a flat rear, *a*, and a front surface made up of zigzag bands *b* and diamond-shaped recesses *d*. It is immaterial whether the strip is a triangle or half-square, a half-hexagon, or a half-octagon, as the effect is substantially the same in

any of these cases. Thus in the drawings I have shown a triangular or half-square strip, Fig. 1, with two bands *b* and three rows of recesses *d*, and in Fig. 2 a half-hexagon strip with three bands *b* and four rows of recesses *d*. 25

I claim—

The within-described design for a molding, said design comprising a strip with flat rear and a front surface made up of zigzag bands *b* and diamond-shaped recesses *d*, as shown and described. 30

In testimony whereof I have signed my name to this specification in the presence of two subscribing witnesses.

WM. SMITH.

Witnesses:

JOHN M. CLAYTON,
HARRY SMITH.
